WALL BRACKET FOR SUPPORTING KEROSENE LAMPS OR THE LIKE

Jerry E. Alexander, Idabel, Okla., assignor to First Step
House Incorporated, Idabel, Okla.

Filed Apr. 13, 1973, Ser. No. 351,024

Term of patent 14 years

Int. Cl. D6—06

U.S. Cl. D8—247

FIG. 4

FIG. 5

FIG. 6

FIG. 1 is a perspective view of a wall bracket for supporting kerosene lamps or the like showing my new design;

FIG. 2 is a side elevation view thereof;

FIG. 3 is a front elevation view thereof;

FIG. 4 is a rear elevation view thereof;

FIG. 5 is a top plan view thereof; and

FIG. 6 is a bottom plan view thereof.

I claim:

The ornamental design for a wall bracket for supporting kerosene lamps or the like, substantially as shown.
